Primary Examiner — S. Bryan Reinholdt, Jr.*Assistant Examiner* — James T Tyree**CLAIM**

The ornamental design for a toy car, as shown and described.

DESCRIPTION

FIG. 1 is a front, left and top perspective view of a toy car, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings illustrate portions of the toy car that form no part of the claimed design.
